US0D1093361S

(12) **United States Design Patent** (10) **Patent No.:** **US D1,093,361 S**
(45) **Date of Patent:** **** Sep. 16, 2025**

(54) **CASE FOR MOBILE ELECTRONIC DEVICE WITH STYLUS PEN**

(71) Applicant: **Samsung Electronics Co., Ltd.**, Suwon-si (KR)

(72) Inventors: **Jieun Myung**, Suwon-si (KR); **Kihwan Kwon**, Suwon-si (KR); **Namsu Kim**, Suwon-si (KR); **Miri Lee**, Suwon-si (KR); **Jinwoo Lee**, Suwon-si (KR); **Jiyoung Lim**, Suwon-si (KR); **Sungwook Lee**, Suwon-si (KR); **Dahyun Lee**, Suwon-si (KR); **Duyeong Choi**, Suwon-si (KR)

(73) Assignee: **SAMSUNG ELECTRONICS CO., LTD.**, Suwon-si (KR)

(**) Term: **15 Years**

(21) Appl. No.: **29/905,155**

(22) Filed: **Oct. 17, 2023**

(30) **Foreign Application Priority Data**

Apr. 19, 2023 (KR) 30-2023-0015106

(57) **CLAIM**

The ornamental design for a case for mobile electronic device with stylus pen, as shown and described.

DESCRIPTION

FIG. 1 is a top front perspective view of a case for mobile electronic device with stylus pen showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top rear perspective view thereof; and,

FIG. 9 is another top front perspective view of the case for mobile electronic device with stylus pen shown in FIG. 1, showing the case for mobile electronic device without the stylus pen.

The dashed broken lines in the figures depict portions of the case for mobile electronic device with stylus pen that form no part of the claimed design.

1 Claim, 9 Drawing Sheets
